UNITED STATES PATENT OFFICE.

CHARLES F. KNAPP, OF BROOKLYN, NEW YORK.

DESIGN FOR A RING.

SPECIFICATION forming part of Design No. 27,930, dated December 7, 1897.

Application filed October 23, 1897. Serial No. 656,214. Term of patent 31 years.

To all whom it may concern:

Be it known that I, CHARLES F. KNAPP, a citizen of the United States, and a resident of Brooklyn, county of Kings, and State of New York, have invented and produced a new and original Design for Rings, of which the following is a full, clear, and exact specification, reference being had to the accompanying drawings, wherein—

10 Figure 1 is an enlarged view of the design. Fig. 2 is a perspective view of a ring to which the design is applied.

15 The design comprises the plastic ornament connecting the head-plate *a* to the band *b* of the ring.

20 The leading feature of the design is the arrangement of artistic scrolls *c*, *d*, and *e* and the arrangement of the four-pointed rosettes upon the bands *f* and upon the matted fields 25 between the scrolls *d* and *e*.

The ornament surrounds the head-plate of the ring and is arranged symmetrically on both sides thereof.

25 The head-plate of the ring is elliptical and placed in a slanting position transversely to the band *b*. Strips *f*, forming the stems of scrolls *e*, start from the top and bottom of the head-plate and are curved in a line corresponding to but deviating from the contour 30 of its edge.

The angular spaces between the edge of the head-plate and the deviating edges of strips *f* are filled by foliage scrolls *c*. The foliage scrolls *d* are similarly arranged between the

opposite edges of the strips *f* and the termini 35 of the scrolls *e*.

Strips *f* have an even matted surface whereupon five four-pointed rosettes are set, the largest in the centers of these strips, and on each side thereof are arranged smaller ro- 40 settes equidistantly from each other, diminish- 45 ing successively in size toward both ends of the strips.

The fields between the scrolls *e* and *d* are also matted like the surface of the strips *f*, 45 and four-pointed rosettes, larger in size than those set upon the strips, are set thereupon 50 concentrically with the inner curves of the scrolls *d*.

The most outwardly-projecting parts of the 50 scrolls *e* and two concaved circles *g* and *g'*, successively diminishing in size, set on the band in line with them, form the termini of the ornament, connecting the same with the band of the ring. The raised edges and faces 55 of the scroll may be scalloped or smoothly finished.

I claim—

60 The design for a ring as herein shown and described.

In witness that I claim the improvements described in the foregoing specification I have signed my name in the presence of two sub- 65 scribing witnesses.

CHARLES F. KNAPP.
